(74) Attorney, Agent, or Firm — Calfee, Halter & Griswold LLP

(57) **CLAIM**

The ornamental design for a clipboard, as shown and described.

DESCRIPTION

FIG. 1 is a perspective view of a clipboard showing our new design;

FIG. 2 is a right side view of the clipboard shown in FIG. 1; FIG. 3 is a left side view of the clipboard shown in FIG. 1; FIG. 4 is a front view of the clipboard shown in FIG. 1; FIG. 5 is a rear view of the clipboard shown in FIG. 1; FIG. 6 is a top view of the clipboard shown in FIG. 1; and, FIG. 7 is a bottom view of the clipboard shown in FIG. 1. The broken lines showing the clip and attachment features in FIGS. 1-7 are included for the purpose of showing features that form no part of the claimed design.

1 Claim, 4 Drawing Sheets
